US00D562117S

(12) **United States Design Patent** (10) Patent No.: **US D562,117 S**
Dubon (45) Date of Patent: **** Feb. 19, 2008**

(54) **HEAVY DUTY TELESCOPING SLIDE
HARDWARE**

(75) Inventor: **William Dubon**, Bloomingdale, IL (US)

(73) Assignee: **Pentair Electronic Packaging Co.**, Des Plaines, IL (US)

(**) Term: **14 Years**

(21) Appl. No.: **29/244,693**

(22) Filed: **Dec. 13, 2005**

(51) LOC (8) Cl. **08-05**

(52) U.S. Cl. **D8/374**

(58) Field of Classification Search **D8/374,
D8/499; 312/323, 333, 334.39; 211/26**
See application file for complete search history.

(57) **CLAIM**

The ornamental design for a heavy duty telescoping slide hardware, as shown.

DESCRIPTION

FIG. 1 is a perspective view of a heavy duty telescoping slide hardware showing the new design;

FIG. 2 is a front elevational view;

FIG. 3 is a rear elevational view;

FIG. 4 is a right side elevational view;

FIG. 5 is a left side elevational view;

FIG. 6 is a top plan view;

FIG. 7 is a bottom plan view;

FIG. 8 is a perspective view of a second embodiment of the heavy duty telescoping slide hardware of FIG. 1;

FIG. 9 is a front elevational view of the second embodiment;

FIG. 10 is a rear elevational view of the second embodiment;

FIG. 11 is a right side elevational view of the second embodiment;

FIG. 12 is a left side elevational view of the second embodiment;

FIG. 13 is a top plan view of the second embodiment;

FIG. 14 is a bottom plan view of the second embodiment; and

FIG. 15 is a perspective view of a third embodiment of the heavy duty telescoping slide hardware of FIG. 1;

FIG. 16 is a front elevation view of the third embodiment;

FIG. 17 is a rear elevation view of the third embodiment;

FIG. 18 is a right side elevation view of the third embodiment;

FIG. 19 is a left side elevation view of the third embodiment; and

FIG. 20 is a top plan view of the third embodiment; and,

FIG. 21 is a bottom plan view of the third embodiment.

The broken line showing is for illustrative purposes only and forms no part of the claimed design.
